UNITED STATES PATENT OFFICE.

HENRY BEAUFORD, OF KANSAS CITY, MISSOURI.

MOTOR ROLLER-SKATE.

No. 823,385.

Specification of Letters Patent.

Patented June 12, 1906.

Application filed October 2, 1905. Serial No. 281,040.

To all whom it may concern:

Be it known that I, HENRY BEAUFORD, a citizen of the United States, residing at Kansas City, in the county of Jackson and State 5 of Missouri, have invented certain new and useful Improvements in Motor Roller-Skates; and I do declare the following to be a full, clear, and exact description of the invention, such as will enable others skilled in the art to 10 to which it appertains to make and use the same.

My invention relates to improvements in roller or cycle skates, and more particularly to one which is self-propelled.

The object of the invention is to provide an 15 automobile skate which will be simple and durable in construction and convenient and efficient in operation.

With the above and other objects in view the invention consists of certain novel features of construction, combination, and arrangement of parts, as will be hereinafter described and claimed.

In the accompanying drawings, Figure 1 is 20 a side elevation of one of my improved automobile skates. Fig. 2 is a similar view of the opposite side of the same. Fig. 3 is an end elevation, and Fig. 4 is a vertical transverse sectional view.

The embodiment of my invention shown in 25 the accompanying drawings comprises a body 1, which is adapted to be secured to a persons foot and which is mounted upon supporting-wheels 2, which are geared to a motor 3, carried by said body. The body 1 and its supporting-wheels 2 are preferably constructed 30 similar to the bicycle or cycle skates now in general use; but they may be of any other form and construction from that shown. The body 1 comprises a base-plate 4, which has 35 an extended rear portion 5 and depending brackets or hangers 6 upon its under side. The base 4 is shaped to fit a shoe and is secured thereto by the usual straps 7, the heel of the shoe resting in the usual heel portion 40 of the skate. The supporting and drive wheels 2, of which two are preferably provided, one being at the front and one at the rear, are suitably journaled in bearings in the 45 brackets or hangers 6, and they are preferably provided with rubber rims or tires, as 50 shown.

The motor 3, which is here shown in the 55 form of an explosive or gasolene motor, is suitably secured, as shown at 9, upon the extended portion 5 of the base 4 and it may be of any suitable construction. As shown, its

operating parts are disposed in a casing 11, through bearings in which extends a power-shaft 12. On one end of the shaft 12 is secured a bevel-gear 13, which meshes with a 60 bevel-pinion 14, secured upon one end of a shaft 15, which is journaled in bearings 16, provided upon the casing 11 and the rear hanger 6. On the opposite end of said shaft is secured a bevel-gear 17, which meshes with 65 a similar gear 18, secured upon one end of the shaft 19 of the rear wheel 2. Upon the opposite end of the shaft 19 is provided a similar bevel-gear 20, which meshes with a bevel-pinion 21 upon a longitudinally-extending 70 shaft 22, mounted in suitable hangers or brackets 23, as clearly shown in Fig. 2 of the drawings. The shaft 22 has upon its opposite end a bevel-pinion 24, which meshes with a bevel-gear 25, secured upon one end of the 75 shaft 26 of the front wheel or roller 2. It will be seen that when the power-shaft 12 of the motor is in operation its motion will be imparted, through the gearing just described, to the two wheels 2, so as to rotate the latter 80 and propel the skate.

As previously stated, the gasolene-motor 3 may be of any well-known or preferred construction, and, as shown, has supported from its casing a carbureter 27, to which oil and 85 air are supplied through suitable pipes 28 29. The oil-supply pipe 28 contains a suitable controlling-valve 30, which is here shown in the form of an angle-cock and leads from a gasolene tank or container 31, which is supported beneath the base 4 of the skate in rear of the front wheel 2 upon a suitable frame 32, which connects the front and rear hangers or brackets 6. The lever 33 on the cock or valve 30 is adapted to be operated by hand, 90 and this is preferably done by means of a cord or other flexible connection 34, which has one of its ends attached to the lever 33 and its other end supported upon the person of the user of the skate within convenient reach. 95 The air-supply pipe 29 is also provided with a suitable controlling valve or cock 35 and leads to one end of an air tank or container 36, which is supported upon the frame 32 in rear of the oil-tank 31 and in front of the rear 100 wheel 2. The tank is supplied with air through a pipe 37, which leads from an air-pump 38, mounted upon the front hanger or bracket 6, as shown. This pump 38 may be of any desired form and construction and is 105 actuated by connecting its pitman-rod 39 by means of an eccentric-strap 40 to an eccentric

disk 41, secured upon one end of the shaft 26 of the front wheel 2. It will be seen that as the latter is rotated the pump will be actuated to pump air into the tank 36. The engine or motor 3 may be provided with a lubricating device 42 of any suitable form, which is preferably mounted upon the outside of the casing 11, as shown.

- In the top of the cylinder of the motor I
- 10 provide an air cock or valve 43 of any well-known or preferred form. In order to brake the speed of rotation of the wheels in descending a hill or when it is desired to stop, I provide in the exhaust-pipe 44, which leads from the exhaust of the engine to a muffler 45, a valve 46, which is operated by a cord or the like 47, connected to its lever, as shown. The valve 46, which is similar to the valve 30, is normally in its open position, so that when
  - 15 said cord 47 is drawn upon the valve will be closed or partially closed. When this is done the air in the engine-cylinder above the piston will cushion the upward movement of the latter and cause the same to act as a brake for the skate. If desired, a cushion-pad 48 may be provided on the base 4 of the skate. This pad may be of solid rubber, as shown, or in the form of a pneumatic or hollow air-cushion.
  - 20 From the foregoing description, taken in connection with the accompanying drawings, the construction and operation of the invention will be readily understood without requiring a more extended explanation.
  - 25 Various changes in the form, proportion, and the minor details of construction may be resorted to without departing from the principle or sacrificing any of the advantages of this invention.
  - 30 Having thus described my invention, what

I claim as new, and desire to secure by Letters Patent, is—

1. An automobile skate comprising a body having front and rear supporting-wheels, each provided with a gear-wheel, a longitudinal shaft having gear-wheels engaging the first-mentioned gear-wheels, an explosive-motor mounted on the body and having its power-shaft geared to one of the supporting-wheels, and an air-tank and a gasolene-tank 45 for supplying the motor and arranged under the body between the said supporting-wheels.

2. The herein-described automobile skate comprising the body having the rear extension, and front and rear supporting-wheels, 50 each provided with a gear-wheel, the explosive-motor mounted on the rear extension and having the exhaust provided with the valve 46, said valve having the operating-cord 47; the air and gasolene tanks arranged under the body between the supporting-wheels, the supply-pipe leading from the gasolene-tank to the carburetor of the motor and having the valve 30 provided with the operating-cord 34; the longitudinal shaft having 55 the gears engaging those of the supporting-wheels, driving connections between the shaft of the motor and the rear supporting-wheel, and the air-pump under the front portion of the skate-body and connected to and operated by the shaft of the front supporting-wheel.

In testimony whereof I have hereunto set my hand in presence of two subscribing witnesses.

HENRY BEAUFORD.
